EMERGENCY MEANS FOR FLOATING SHIPS

Filed Dec. 30, 1920

Inventors:
Frederick Y. Nichols
Samuel R. Drum
By *James Paul Hinsley Atty*

UNITED STATES PATENT OFFICE.

FREDERICK Y. NICHOLS AND SAMUEL R. DRUM, OF CHICAGO, ILLINOIS; SAID SAMUEL R. DRUM ASSIGNOR TO WILLIAM HENRY DRUM, OF GRIDLEY, ILLINOIS.

EMERGENCY MEANS FOR FLOATING SHIPS.

Application filed December 30, 1920. Serial No. 434,116.

To all whom it may concern:

Be it known that we, FREDERICK Y. NICHOLS and SAMUEL R. DRUM, citizens of the United States, residing at Chicago, in the county of Cook and State of Illinois, have invented certain new and useful Improvements in Emergency Means for Floating Ships, of which the following is a specification.

10 The invention relates to emergency means for maintaining the buoyancy of a floating vessel or ship that may be damaged.

One of the objects of the invention is to provide a means that may quickly be brought into action to preserve the buoyancy of a damaged ship that otherwise would sink.

Another object is to provide a means, as above set forth, that will normally occupy 20 a relatively small space; that is very light of weight; that is simple in construction and operation and inexpensive to produce.

Another object is to provide a system, as above set forth, that may be used to float 25 and recover a sunken ship.

Other, further and more specific objects of the invention will become readily apparent, to persons skilled in the art, from a consideration of the following description, 30 when taken in conjunction with the drawing.

In the drawing, 5 is a conventional representation of a ship shown in central section. 35 6 represents collapsible, expandible rubber, or other air receptacles, adapted to be inflated by air and capable of expanding extensively and to be readily collapsed when exhausted of the air. These air receptacles may be placed in the hull of a ship, at convenient locations, in staterooms or in other places normally unoccupied by the cargo.

40 7 shows an elongated receptacle placed in the hull of the ship and which may extend from end to end of the ship, and which resembles, in some degree, an enlarged hose when inflated, but which will lie flat when deflated, and occupy a relatively small space. In a ship there may be a plurality of air receptacles of this character, located at convenient places and capable of being readily expanded upon the introduction of air under pressure.

45 8 shows an air compressor, adapted to be operated by a special engine 9, preferably located upon the deck of a ship, and prefer-

ably this motor or engine should be operated by a locally applied fuel or energy rather than the steam generated by the boilers 10, that are located in the hull of a ship, so that in the event that the hull should become 60 filled with water, the operation of the engine 9 is available. An internal combustion engine or an electric motor operated by storage batteries are fair examples of the character of motor well adapted for the purpose. 65

11 and 12 represent large tanks that may be kept filled with air under pressure, and 13 and 14 are pipes leading from both of the tanks to the various receptacles 6 and 7. 15 15 and 16 are valves that may be opened to admit air into the various receptacles 6 and 7, when an emergency arises. In such an event the engine 9 may be started and the compressor will immediately begin to force air thru the pipes 13 and 14 into the various 75 expansible air receptacles. 17 is a stand-pipe communicating with the air pipes 13 and 14 and covered normally with a cap 18. In the event that a ship should sink, a diver has only to remove the cap and connect the 80 hose to the pipe when air from above may be pumped into the various receptacles 6 and 7, and thereby the receptacles will become inflated and enlarged, driving the water out of the hull and causing the ship 85 to rise to the surface.

The air containers, 6 and 7, may be made of relatively thin rubber that is capable of great expansion. They will not be called upon to withstand very high pressure because the external pressure and internal pressure will be substantially equalized by the pressure of the water on the outside of the receptacles. 90

In the case of war, where the ship's hull has been damaged below the water-line, the receptacles located in the hull may be inflated and the hull kept afloat by the means herein disclosed. Other forms of expandible receptacles made of other material than rubber will undoubtedly be suggested to persons skilled in the art. 95

Having described our invention what we claim as new and desire to secure by Letters Patent is:— 100

In a ship, a plurality of expandible air receptacles located in various parts of the vessel; an air reservoir located at each end of the vessel; means near each reservoir for controlling the reservoirs in the event that 110

the other reservoir-controlling means has become inaccessible; pipes connecting the receptacles and the reservoirs; an air compressor for charging the reservoirs selectively; means for operating said compressor independently of the power means that drives the ship and means on the deck of the

ship by which an air conducting hose may be connected to the system.

In testimony whereof we hereunto set our hands.

FREDERICK Y. NICHOLS.
SAMUEL R. DRUM.
